United States Patent Office.

JOSEPH D. HALL, OF TRENTON, NEW JERSEY.

Letters Patent No. 95,898, dated October 19, 1869.

IMPROVEMENT IN RULERS.

The Scher^ore referred to in these Letters Patent and making part of the same.

I, JOSEPH D. HALL, of the city of Trenton, county of Mercer, and State of New Jersey, have invented an Improvement in Rulers, to be known and designated as the "Blotting-Pad Ruler," of which the following is a specification.

My invention relates to the combination of the ruler and blotting-pad, in such a manner as to render it impossible for the ink, or other liquid used for ruling-purposes, to come in contact with the paper or substance ruled or written upon, except as it is done through the nib or point of the writing or ruling-pen, the blotting-pad at all times presenting a surface between the ruler and the thing ruled, the frame being extended on either side beyond the lower edge of the ruler, and intercepting any ink which might otherwise flow from the edge of the ruler to the paper to be ruled.

The frame which holds the blotting-pad is attached to the ruler by a hinge and pins, as shown in the accompanying drawing. I do not limit myself to this nor any particular manner of attaching the frame. It may be done by pins or clasps, attached to each end of the ruler and frame, or by a hinge and clasp, or in such other way as may be most desirable and convenient. The blotting-pad is folded around the frame, and the edges fastened with mucilage. It can be slipped from the frame and changed at pleasure. This permits the use of either side of the blotting-pad, but it is not necessary that it should be fastened at the edges, as the frame, when the ruler is closed upon it, will be sufficient to hold the blotting-pad in position.

Description of the Accompanying Drawings.

Figure 1 shows the top of the ruler; A, the dotted lines; B B, the blotting-pad; C C, the frame; D D, pins holding the frame to the ruler; and E, the hinge connecting the ruler and frame.

Figure 2 shows the end of the ruler; A, the top; B B, the blotting-pad; C, the frame; D D, pins.

Figure 3 shows one edge of the ruler.

Figure 4 shows the blotting-pad, B B; C C, the frame, around which the blotting-pad B B is folded.

Figure 5, the end of the blotting-pad and frame.

I disclaim all rulers having but one roller and blotter attached, and which is to act as ruler, blotter, and paper-cutter.

I also disclaim the combination known as the "combination of blotter, paper-weight, rule, cutter, and square."

I also disclaim, the "improvement in blotting-pad," all these having been heretofore known and used.

Claim.

I claim, as my invention—

The combination, of the ruler and blotting-pad with the frame which holds the blotting-pad, and the manner of attaching them, substantially as described, and for the purposes hereinbefore set forth.

JOSEPH D. HALL.
